DESIGN FOR A HANDLE FOR TOOLS OR SIMILAR ARTICLES

Harry B. Curtis, Huntington, Conn., assignor to The Bridgeport Hardware Manufacturing Corporation, Bridgeport, Conn., a corporation of Connecticut

Application March 22, 1937, Serial No. 68,335

Term of patent 7 years

To all whom it may concern:

Be it known that I, Harry B. Curtis, a citizen of the United States, residing at Huntington, county of Fairfield, State of Connecticut, have invented a new, original, and ornamental Design for a Handle for Tools or Similar Articles, of which the following is a specification; reference being had to the accompanying drawing, forming part thereof.

Fig. 1 is a side elevation of a handle for tools or similar articles, showing my new design.

Fig. 2 is a side elevation thereof looking from the right of Fig. 1, and

Fig. 3 is a top plan view thereof.

I claim,

The ornamental design for a handle for tools or similar articles, substantially as shown.

HARRY B. CURTIS.
